UNITED STATES PATENT OFFICE

2,481,944

AIR-COOLED BLOCK

Norman H. Nye, Cuyahoga Falls, Ohio, assignor
to The Vaughn Machinery Company, Cuyahoga
Falls, Ohio, a corporation of Ohio

Application June 2, 1945, Serial No. 597,209

1 Claim. (Cl. 205—20)

1

The present improvements, relating as indicated to wire drawing blocks, have more particular regard to means for cooling such block and the coil of wire wrapped thereon during a drawing operation.

As is well known, the wire as it is drawn through a die becomes highly heated and if not cooled between successive passes the temperature of the wire may become excessively high with resultant injury. The usual method for effecting such desirable cooling has been to spray water or equivalent liquid coolant onto the interior surface of the block or drum, but this involves the difficulty that any liquid thus employed has a tendency to enter the bearings which support the block; also due to centrifugal force the removal of the liquid from the block in desired manner and at desired rate presents a further difficulty.

One principal object of the present invention is the provision of cooling means which will permit the employment of air or equivalent gaseous coolant instead of such liquid. While it has been heretofore proposed to use air, there has been a lack in previous constructions of means whereby such gaseous coolant can be used in adequate volume and a maximum cooling action secured therefrom.

A more particular object of the present invention, accordingly, is the provision of a block or drum through which a gaseous coolant may be circulated without undue impediment to its flow, thus permitting such flow at a maximum rate, and at the same time to secure maximum absorption of heat. Still another object is to provide a construction of block which will be extremely simple with no complicated parts or connections for supplying the cooling fluid, e. g. air, to the block.

To the accomplishment of the foregoing and related ends, said invention, then, consists of the means hereinafter fully described and particularly pointed out in the claim.

The annexed drawing and the following description set forth in detail certain mechanism embodying the invention, such disclosed means constituting, however, but one of various mechanical forms in which the principle of the invention may be used.

In said annexed drawing:

Fig. 1 is a transverse horizontal section through a wire drawing block embodying my present improvements;

Fig. 2 is a central vertical section thereof, including the supporting structure whereon the

2

block is mounted, the plane of the section being indicated by the line 2—2 Fig. 1; and

Fig. 3 is a broken vertical section of the block, the plane of such section being indicated by the line 3—3 Fig. 2.

Referring to the several figures of the drawing, a block 1 whereon the wire is wound in the usual manner during the drawing operation is mounted on the upper end of a vertical spindle 2 suitably journalled in a supporting frame structure 3. Only the portion of the latter adjacent the block is shown and it will be understood an additional, step bearing will be provided for the lower end of said spindle and that there will be suitable driving connections for the latter. It will also be understood that while, as illustrated, the spindle is vertically disposed, it may equally well extend in a horizontal direction as in certain types of wire drawing benches.

20 Feed block or drum 1 is mounted on the end of spindle 2 through the medium of a hub 4, the drawing face of the block being formed by a depending annular flange 5 spaced from such hub. The wire engaging surface of the block or drum is bounded above and below by bevelled flanges 6 and 7 respectively, so that the wire at it is wound thereon will be held against displacement.

25 The portion of the supporting frame structure 30 3 adjacent the block or drum 1 includes an upstanding hollow flange 8 which closely contacts the lower flange 7 of said block and is provided with a plurality of inwardly directed apertures 9 adjacent such line of contact, such apertures 35 inclining toward the wire-engaging surface of the block so as to direct thereagainst air or equivalent cooling fluid supplied to the annular chamber 10 within said hollow flange 8 from a chamber 11 connected with a source of such 40 cooling fluid maintained under suitable pressure.

30 Stationarily supported on frame structure 3 is an annular partition 12 that extends upwardly within the space between the hub 4 and depending flange 5 of the block or drum 1, whereby 45 such space is divided into two concentric chambers. Such partition is formed with an opening 14 which communicates with the outer such space, and a second opening 15 at the opposite side connects such outer space with such inner space, for which latter an exit opening 16 is formed in the upper face of the block or drum. The chamber 10 in flange 8 is connected by means of one or more openings 17 with the annular chamber 18 bounded by frame structure 3, 55 such flange 8 and the lower portion of the de-

pending flange 5 of the block. As a result, the cooling fluid received in chamber 10 from duct 11 in addition to discharging through the openings 9 will enter into said chamber 18 and thence, by way of opening 14 in partition 12, into the outer annular space formed by said partition within the block, circularly around the latter to opening 15 through which it will pass into the inner space in the block and thence out through exit opening 16 in the upper face of the latter. As a result it will be seen that a divided stream of the cooling fluid will be caused to circulate within the block in contact with the inner face of depending flange 5 and to enhance the cooling action such face is formed with a plurality of inwardly directed circumferentially directed ribs or fins 20.

The mode of operation of my improved block should be apparent from the foregoing description of the construction of its component parts and the manner in which the cooling stream of air or equivalent fluid is circulated within the same. At the same time jets of the cooling fluid will be discharged against the wire-engaging surface of the drum or the coils of wire as they are wound thereon. However, the important improvement consists in the highly efficient means provided for withdrawing heat from such surface through the circulation of the cooling fluid between the inwardly directed ribs or fins 20. The latter insure a close and equalized contact of the cooling stream throughout the entire inner face of the depending flange 5, so that by maintaining the proper rate of flow and temperature of the fluid used, any desired degree of cooling action may be obtained. At the same time the construction of the block is relatively simple, there being no separate moving parts other than the block itself.

Other modes of applying the principle of my invention may be employed instead of the one explained, change being made as regards the mechanism herein disclosed, provided the means stated by the following claim or the equivalent of such stated means be employed.

I therefore particularly point out and distinctly claim as my invention:

- A rotatably mounted block including a hub portion and an annular flange extending from said hub portion with its axis aligned therewith, a base, means rotatably mounting said block on said base, and means for cooling said block comprising a plurality of annular ribs secured to the inner circumference of said flange at spaced distances longitudinally thereof forming a plurality of closed circular channels opening inwardly, a stationary annular partition secured to said base and concentric with said cylindrical flange and effectively closing the opening of said channels except for an air inlet passage and an air outlet opening set forth hereinafter, said partition including a stationary longitudinal air inlet passage communicating with said circular channels and a longitudinal air outlet opening diametrically opposed to said air inlet passage for communicating said channels with the space within said partition, an opening in said hub portion, and means for supplying air to said air inlet passage, whereby air will flow through said air inlet passage, in opposite directions about said circular channels, outlet opening to the inside of said partition, and exhaust through the opening in said hub portion, the rotation of said annular flange past said stationary air inlet passage continually changing the entrance locality of air passing into said channels.
